UNITED STATES PATENT OFFICE.

RALPH E. DUCKETT, OF SAN FRANCISCO, CALIFORNIA.

COMBINED FORK AND SPOON.

1,271,679.

Specification of Letters Patent.

Patented July 9, 1918.

Application filed January 17, 1918. Serial No. 212,192.

To all whom it may concern:

Be it known that I, RALPH E. DUCKETT, a citizen of the United States, residing at San Francisco, in the county of San Francisco, 5 State of California, have invented a new and useful Combined Fork and Spoon, of which the following is a specification in such full and clear terms as will enable those skilled in the art to construct and use the same.

10 This invention relates to a combined fork and spoon, and its object is to produce a fork and spoon for the purpose of basting or turning roasts when cooking, or for the purpose of expediting service in a cafeteria, or 15 restaurant, the object being to provide in a single instrument either a fork or a spoon as may be required by the operator at the moment.

Other objects of the invention will appear 20 as the description proceeds.

An embodiment of the invention is shown in the drawings in which the same reference numeral is applied to the same portion throughout, but I am aware that there may 25 be modifications thereof.

Figure 1 is a plan view of the combined fork and spoon.

Fig. 2 is a side elevation of the combined fork and spoon,

30 Fig. 3 is a side elevation of the combined fork and spoon showing the fork retracted when the spoon is to be used for basting purposes or for dipping up gravy.

Fig. 4 is a bottom plan view of the end of 35 the spoon handle, and

Fig. 5 is a transverse sectional view of the spoon on the line 5—5 Fig. 1.

The spoon is shown at 1, and it has a suitable flat handle 2, which is turned over at 40 the end as illustrated at 3 for the purpose of holding the fork and spoon in either one of the two positions in which they are normally used in a manner to be presently explained. The spoon has in the bottom 45 thereof two channels 5 and 6 through which the fork tines pass. The fork has two tines 7 and 8, which tines are twisted together as illustrated at 9 and widen at 10 to form a slot through which the down-turned portion 50 3 of the spoon handle can travel. The rela-

tion of the fork to the spoon is such that when the fork tines are withdrawn into the spoon as illustrated in Fig. 3, the down-turned portion 3 of the spoon handle 2 will engage the widened portion 10 of the fork 50 handle with sufficient force to prevent the accidental dislodgment of the fork and spoon from each other.

When the fork tines are projected beyond the spoon, the end of the spoon handle may 60 be forced over the end of the fork handle, as illustrated in Figs. 1 and 2, and the frictional engagement of the two handle ends will be sufficiently stiff to prevent the accidental dislodgment of the fork and spoon 65 in that position as well.

Should it be desired to use the two instruments separately, they may be immediately separated by separating the handles from each other and pulling the fork out of the 70 spoon.

Having thus described my invention what I claim as new and desire to secure by Letters Patent of the United States is as follows, express reservation being made of per- 75 missible modifications.

1. A combined fork and spoon comprising a spoon having passageways through the bowl thereof and having a handle, a fork having a handle carrying tines adapted to 80 pass through the passageways of the spoon bowl, and means whereby the fork and spoon handles may be frictionally connected together at their ends in either one of two positions.

2. A combined fork and spoon comprising a spoon having longitudinally extending passageways through the bowl thereof and a fork having tines adapted to pass through said passageways in the spoon bowl, the handle of said fork having a wide slot therein through which the end of the spoon handle moves, and being adapted to be secured to the spoon handle in either one of the two 90 positions.

In testimony whereof I have hereunto set my hand this 5th day of January, A. D. 1918.

RALPH E. DUCKETT.
